CLAIM

We claim the ornamental design for a thermostat, as shown and described.

DESCRIPTION

FIG. 1 is a top right perspective view of a thermostat; FIG. 2 is a front view according to the claimed design; FIG. 3 is a rear view according to the claimed design; FIG. 4 is a left side view according to the claimed design; FIG. 5 is a right side view according to the claimed design; FIG. 6 is a top view according to the claimed design; and, FIG. 7 is a bottom view according to the claimed design. Any portion of the article depicted in broken lines forms no part of the claimed design. Oblique lines illustrate a reflective or glossy surface, and not surface ornamentation.

1 Claim, 5 Drawing Sheets
